4 Claims

ABSTRACT OF THE DISCLOSURE

A baseball game apparatus employing a board as a playing field with peripheral frame therearound and with the indicia designating a baseball diamond adjacent one corner of the board; with depressions on said diamond designating the bases and home plate; with green areas applied to said board covering infield and outfield, a die rolled by the pitcher to determine the nature of a ball thrown, including strikes, balls and hits; an apertured disc slidably movable over said board, a cue alternately used by offensive and defensive players for sliding said disc and a three dimensional character movably positioned within the base defining depressions of said diamond; there being a plurality of variously colored areas applied to said diamond for designating base hits and "outs."

Heretofore various types of game apparatus have been defined entitled baseball games, however it is the object of the present invention to provide a novel form of game apparatus including a series of structural elements; namely, game board with frame, a die, a cue, a movable disc pushed by said cue by the players corresponding to offensive and defensive sides to thus provide the baseball game following accurately the conventional playing rules of baseball.

It is another object of the present invention to provide a baseball game apparatus which includes upon a board defining a playing field plural areas of different colors and differently marked which upon sliding of the disc over the board and onto a particular area will designate the various plays found in conventional baseball, including bunts, hits, and "outs."

These and other objects will be seen from the following specification and claims in conjunction with the appended drawing in which:

FIG. 1 is a perspective view of the present game board.

FIG. 2 is a plan view of a cue as a part of the game apparatus.

FIGS. 3, 4, 5 respectively show in perspective the disc, a three dimensional character corresponding to a base runner, and a die.

It will be understood that the above drawing illustrates a preferred embodiment of the invention, and that other embodiments are contemplated within the scope of the claims hereafter set forth.

Referring to the drawing the game apparatus includes the upright hollow square frame 1, which defines a fence enclosure. Upon the interior wall of said frame there is provided an elongated undercut groove adapted to cooperatively receive the peripheral edges of the square board 23, which is normally spaced below the upper edge of said frame defining a playing field for a baseball game.

Indicia is applied to one corner area of the board defining baseball diamond 27 including the elongated foul lines 14, there being a series of spaced depressions 16 formed in said board around said diamond and at the corners thereof indicating home, first, second and third bases.

The playing field has applied thereto green colored areas 26 to define the infield and outfield.

2

Outwardly of the diamond and formed of L-shape is the yellow colored strip 11 which is diametrically spaced from the home plate of the diamond for designating a "hit."

Generally parallel to yellow strip 11 is a first L-shaped red strip 10 applied to said board and spaced outwardly from the said yellow strip. The second L-shaped strip 3 also colored red is spaced outwardly from red strip 10 and extends along and adjacent the frame 1 diametrically spaced from said diamond, the said red strips designating "out" areas.

Additionally applied to the said board over certain areas of the playing field are oval shaped areas of different sizes and which have a yellow coloring applied thereto and with additional indicia designating one, two, three and four base hits if the slid disc stops thereover; and colored red to designate "a caught fly" if the slid disc stops thereover.

Around a number of the oval shaped areas are peripheral borders colored red as at 4, 6, and 8 to designate "out" if the slid disc shows some of said border therethrough.

As shown in FIG. 1 a pair of oval areas 18 colored yellow and designated with small indicia 1', designate a safe bunt, area 19 colored red designates "out" and the smaller oval areas 20 colored red also designate "out."

There are a pair of oval areas 5 colored yellow with indicia 1', to designate a one base hit, the pair of oval areas 13 colored yellow and with indicia 2' to indicate two base hits, the oval shaped areas 9 colored yellow to indicate two base hits, the single oval shaped area 7 with indicia 3' and colored yellow to indicate three base hit and the single oval shaped area 2 colored yellow and with indicia 4' to indicate a home run.

Outwardly on the board of the elongated foul lines 14, which correspond and designate portions of the diamond 27 or extensions thereof are elongated strips along the adjacent sides of the frame 1 which are colored green and which have applied thereto a series of small ovals 12 colored red for designating "fly out."

Applied to the board 23 adjacent home plate is indicia 17 defining the batting area upon which the apertured disc 15 is selectively applied for pushing by the batter using the elongated cue 21 with round tapered pushing end 22 in a manner similar to a billiard cue.

The apertured disc 15 corresponds to the baseball used in the game and is slid over the board 23 by the offensive and defensive players in a manner set forth in the detailed description and rules set out hereunder.

The base runner is designated by the three dimensional character 24 which in the illustrative form is of cylindrical shape with flat ends. This base runner is applied selectively to any of the three pockets 16 forming a part of the diamond 27 to show the position of the batter or batters with respect to the three bases.

Completing the description of the apparatus there is employed a die 25 of conventional form which is marked with indicia dots 1 to 6 respectively.

The playing board may be of any size from 25" long on a side to 60" or more. The board 23 is depressed with respect to the top edge of frame 1 adapted to retain the slidable disc 15 within the confines of the playing field.

The playing field essentially is colored green as at 26, with the exception of certain L-shaped strips colored yellow and red, to represent grass and for determining the nature of the play that has been made by a batter, who using the cue 21 pushes the disc 15 to try to make it stop on a yellow area which would indicate a safe hit, but which if it stops on any green area it means a ball which is "in play." The defensive player will then

use the cue, attempt to slide the disc 15 into the first base pocket 16 to make the "out."

The two spaced red strips 3 and 10 are used to designate when the disc 15 is slid to these areas as being that the hit ball has been caught by one fielding the ball to make the batter "out."

The other red spots on the board designated by the numerals 12, 19 and 20 indicates that the batter is "out" if the disc stops on them.

With the disc stopping upon the yellow strip 11 designates a single safe hit. However the other yellow spots or areas of oval shape also indicate base hits depending upon the indicia as, for example, areas 18—a bunt or a safe one base hit; areas 9—a safe two base hit; likewise areas 13 for a safe two base hit, area 7 for a three base hit, and area 2 a home run.

The narrow margins around the yellow base hit areas designated red namely at 4, 6 and 8 respectively are provided so that if any red shows through the middle of the disc the batter is "out."

In the illustrative embodiment the foul line 14 designated with a white coloring to correspond to a conventional baseball field.

The designations 1 and 6 on die 25 on showing up upon rolling by the pitcher designate "strikes"; the spots 3 and 5 designate "balls" and the spots 2 and 4 indicate chances for a "hit."

Baseball game rules

The game is played as near like baseball as I can get it. It does not take as many players as does a real game. If more than two wish to play they will field the ball 15 that comes in their portion of the field 26, as the field can be proportioned to those that are going to play. The fielding of the ball means to try to put the batter out by shooting the disk, 15 into the first base pocket 16.

The pitching

(1) A die 35 is used to determine the pitching.
 (2) The one shaking the die will be the pitcher.
 (3) On the die if a (one) or (six) comes up it is called a *strike*.
 (4) If a (three) or (five) comes up, it is called a *ball*.

(5) If a (two) or (four) comes up, the one at bat will put his disk on the *Black Line* 17 at the home plate, and will try to shoot it with the use of cue 21 to rest on the yellow spots marked out on the playing field 1', 2', 3', 4', these are the base hits. If the disk stops so that no other color shows in the middle of the disk than *yellow* it is a hit. Three strikes is out. Four balls is a walk.

Where the disk stops

(1) If the disk stops on the *red* 3, 4, 6, 8, 10, 12, 19, 20 or even shows in the middle of disk 15 the batter is out. This means the ball was caught.

(2) If the disk stops on *Green* 26 the fielder will shoot it from where it stops to pocket 16 (first base). If he puts it in the pocket the batter is out, but if he doesn't the batter is safe; it will be called a hit, not an error. It will be like the play was too slow.

(3) If the disk stops so that *Yellow and green* show the fielder can play on it but only one base not a double play. (Example), if the hit is on yellow marked (one), the fielder will play it to the first base pocket 16. If the yellow is marked (two) it will be played in the second base pocket 16 to make the out.

(4) If the batter puts the disk in the pocket he is out.
 (5) If the batter makes the disk fly off the board he is out.

Foul balls

(1) If the disk stops behind the foul line 14.
 (2) If the disk stops on the foul line it must be half to be called a foul ball.

Stolen base

If the one throwing the die 25 makes it roll off the board on the floor one base will be stolen, either from first to second or second to third, or from third to home.

(2) If the one throwing the die makes it roll in one of the pockets 16 it will be the same as off the board.

(3) If no one is on base and the above happens the batter will take first base, like the batter was hit with the ball.

Errors made

(1) If the one fielding the ball makes it fly off the board when trying to put it in one of the pockets to make an out, it will be an error.

(2) If when shooting first base 16 to make an out he misses and the disk stops on one of the red spots 12 behind the foul line it is an error and in either case the batter 24 will go second.

(3) If when the play is made at second base pocket, he misses, and the disk goes as far as the *red strip* 10, or farther, its an error, the runner will go third, and if it stops on red *behind* the foul line he will go home.

How plays are made

(1) If the man is on a base and a hit is made he will advance as to what the base hit was; if it was one base hit he will take one base, etc.

(2) If a man is on third and a hit is made on red and it is to the far side of the board he can say "I am going home," and the one fielding it, must try to put it in home pocket 16. If he does he will be out, if not its a run. This is called a sacrifice hit.

(3) When the disk stops on green 26 it means the ball is still in play and bases can be advanced if the runner says he is going, and before the fielder plays on it.

(4) If a man 24, is on first and one on second and the batter hits so the disk stops on the two base, hit 13, the one without any red around it, and green shows in the middle, the one fielding it will have to shoot the disk to second. The man 24 that was on second will go home, and the one that was on first will go third. If the pocket is missed it will be a two base hit, if not, the batter is out. The reason for this: The batter has tried to make it a two base hit, he can't say I stay on first, he attempted a two base hit. The other runners get the benefit as though it was a double, but he can be put out.

Double plays

(1) If a man is on first base and the batter hits the disk so it stops on green, it will be played first to the second base and then to the first base. This is done by shooting the disk in the second base pocket then take it out and set it on the right side of the pocket on base line to third base.

(2) When the pocket is missed the play stops. It means the play was too slow.

(3) Another point is, if a number are playing, and a double play is to be made, the shot to the first base will be done by another fielder, same as in baseball.

(4) No double play can be made when the batter shoots the disk so that part green and yellow shows in the middle, it will be played to base indicated on yellow.

(5) If a man is on first base and one on second base, and the batter shoots the disk and it stops on green and is within six inches of *third* base pocket it may be played as a triple play.

Having described my invention, reference should now be had to the following claims. I claim:

1. In a baseball game apparatus; a hollow square frame defining a fence enclosure; a square board peripherally secured within said frame spaced below its upper edge defining a playing field; a die adapted for manual rolling over said board by a pitcher to determine nature of a thrown ball, including strikes, balls and hits, respectively;

an apertured disc slidably mounted on said board starting from a batting area on said board;
a cue alternately used by offensive and defensive players for sliding said disc;
indica upon one corner of said board defining a diamond with foul lines;
there being a series of spaced depressions in said board around said diamond at the corners thereof indicating home, and first, second and third bases;
and a three dimensional character selectively positioned at any of said depressions defining bases to designate position of a base runner.

2. In the baseball game apparatus of claim 1, said board having a green coloring applied thereto to designate the infield and outfield;
there being an L-shaped strip colored yellow on said board adjacent and outwardly of the infield defining a base hit area if the disc stops thereover;
there being an L-shaped strip colored red on said board spaced outwardly from and generally parallel to said first strip;
there being a second L-shaped strip colored red spaced outwardly of the first red L-shaped strip and extending along and adjacent said frame;
said red colored strips defining "batter out" areas if any portion thereof shows through said disc.
3. In the baseball game apparatus of claim 2;
there being a plurality of spaced oval shaped areas of

different size on said board colored yellow with indicia to designate bunts, one, two, three and four base hits, if the disc stops thereover;
and colored red to designate a "caught fly" if the disc stops thereover.

4. In the baseball game apparatus of claim 3;
there being peripheral borders colored red extending around some of the oval shaped areas colored yellow, to designate "out" if the red shows through a "batted" disc.
